UNITED STATES PATENT OFFICE.

WALTER J. MCCOY, OF OMAHA, NEBRASKA; ELIZABETH MCCOY ADMINISTRATRIX OF THE ESTATE OF SAID WALTER J. MCCOY, DECEASED.

HEADER-BRICK MOLD.

Application filed March 18, 1922. Serial No. 544,749.

To all whom it may concern:

Be it known that I, WALTER J. McCoy, a citizen of the United States, residing at Omaha, in the county of Douglas and State 5 of Nebraska, have invented certain new and useful Improvements in Header-Brick Molds, of which the following is a specification.

This invention relates to certain new and 10 useful improvements in molds and pertains more especially to a mold which is employed for making header brick, the latter used in the construction of hollow walls.

The primary object of the invention is to 15 provide a mold which is of simple construction and which has a removable pattern plate so as to allow of the easy and quick removal of one plate and the substitution of another having a different design or pattern.

A further object of the invention is to provide a mold in which the pallet and mold act to hold the pattern plate in molding position and which after molding, the 25 pattern plate can be swung downwardly after raising of the mold and while the tamper is held stationary.

The invention has still further and other objects which will be later set forth and of 30 themselves manifested in the course of the following description.

In the drawings:

Figure 1, is a top plan view of the invention;

Figure 2, is a section on line 2—2 of Figure 1;

Figure 3, is a detail perspective view of the pattern plate, and

Figure 4, is a perspective view of the completed block.

In proceeding in accordance with the present invention, a mold is provided having side walls 1 and end walls 2 and 3 and an open top and bottom. The end walls 45 have similar inward projections with tapering sides 4 extending vertically along their inner faces and located to one side of the center of the side walls. The end wall 3 has a dovetail projection 5 at its center the 50 purpose of which is to form a recess R of corresponding shape in the block B. Studding or strips also of dovetail shape and to which the lathing is nailed is designed to be slid into or otherwise secured 55 in the recesses R upon completion of the

wall. The projections 4 cause the block B to have similar recesses C in the opposed sides of the same, the recesses having inwardly converging sides, though obviously other forms of projections 4 producing varying conformations of recesses may be employed as desired.

A pattern plate 6 is employed having any suitable or desired pattern 7 to produce a corresponding figure D on the front face of the block B. The lower side 8 of the pattern plate is reduced forming a shoulder 9, the latter being seated upon the pallet 10. The pattern plate fits within the mold and is held against the end wall 2 by virtue of the pallet abutting the lower side 8 of the plate 6. The tamper is indicated at 11 and is shaped to fit within the mold interior and to receive and slide past the projections 4, 4 and 5. The side walls 1 of the mold are provided with tongues to engage the mold carrier of my cement block machine, application for patent for which was filed May 14, 1921, Serial No. 469488 and received patent thereon No. 1,438,488, issued Dec. 12, 1922.

The molds are supported and carried by the mold carrier and can be raised or lowered at will by the operator, while the pattern plate is suitably hinged in any desired manner at 30 to the base 25 of the machine and is moved to extend downwardly when not in use, all as set forth in my said copending application.

In assembly of the parts preparatory to molding the mold is raised, the pallet then placed on the base of the machine and finally the pattern plate is turned upwardly with the shoulder 9 resting on the pallet. The mold is then lowered to the position of Figure 2, and is filled with the aggregate and the tamper set in operation. After completion of the tamping, the tamper remains in position in the mold and is held stationary, the mold being then raised by the mold carrier to a position above the pattern plate, following which the pattern plate is turned to extend downwardly and the pallet then removed with the brick thereon.

What is claimed is:

1. In a mold, a body having sides and ends and an open top and bottom, similar projections on the inner faces of the sides, a dovetail projection on the inner face of one

end, a hinged pattern plate having a reduced lower side forming a shoulder and a pallet having an edge thereof engaged with the reduced lower side of the pattern plate 5 and having the shoulder of said plate seated on its upper face whereby to hold the pattern plate in position and engaged within the adjacent mold wall.

2. In a mold, a base, an upwardly movable 10 body supported on the base and having sides and ends and an open top and bottom, projections carried by the body and extending therewithin to form recesses in the molded body, a hinged pattern plate carried 15 by base and engaged with a wall of the mold body, and a pallet seated on the base and closing the bottom of the mold body and formed to support the pattern plate against downward movement toward the mold interior.

3. In a mold, a base, a body on the base having side and end walls and an open top and bottom, a pattern plate hinged to the base and engageable with a wall of the body 25 so as to be held thereby against outward movement, a pallet on the base, and a tamper, said body being upwardly movable from the base and pallet and while the tamper remains stationary to allow the pallet and brick thereon to be removed.

4. In a mold, a base, a body having side and end walls, a pattern plate in the body removably engaged with one of the walls of the body and held against outward movement thereby, and a pallet seated on the base and which removably supports the body and closes the bottom of the body whereby the body can be raised up from the pallet while the latter remains stationary and the pattern 35 plate then removed.

5. In a mold in combination with a tamper, a body having an open top and bot-

tom, a pallet closing the bottom of the mold, and a hinged pattern plate movable to engage the pallet to be held in place by the 45 mold and movable downwardly away from the pallet upon raising of the mold and while the tamper and pallet remain stationary to allow the pallet and the brick thereon to be removed.

6. In a mold, a base, a pallet on the base, a mold body having side and end walls removably disposed over the pallet, and a pattern plate hinged to the base and movable to overlie the pallet and to engage a wall of the mold body so as to be held against outward swinging movement thereby, said mold body being movable upwardly from the pallet and base to allow the pattern plate to be swung away from the pallet and the latter then moved upwardly from the base.

7. In a mold, a base, a pallet on the base, a mold body having side and end walls removably disposed over the pallet, and a pattern plate hinged to the base and movable to overlie the pallet and to engage a wall of the mold body so as to be held against outward swinging movement thereby, said pattern plate having a right-angular shoulder 65 formed to engage against the adjacent end 70 edge and upper face of the pallet so as to be held against inward movement.

8. In a mold, a base, a pallet thereon, a mold body supported from the base, and a hinged pattern plate carried by the base and receivable within the mold body and movable downwardly to a position beneath the pallet, said mold body being vertically movable to permit said downward swinging of the pattern plate thereby to expose and permit free access to the pallet to permit of removal of the latter from the base.

In testimony whereof I affix my signature.
WALTER J. MCCOY.
